UNITED STATES PATENT OFFICE.

WILLIAM F. OAKLEY, OF NEW YORK, N. Y.

CLIP.

No. 883,119.

Specification of Letters Patent. Patented March 24, 1902.

Application filed February 19, 1907. Serial No. 358,301.

To all whom it may concern:

Be it known that I, WILLIAM F. OAKLEY, a citizen of the United States, and resident of New York, in the county of New York and State of New York, have invented certain new and useful Improvements in Clips, of which the following is a specification.

My invention relates to improvements in clips, and particularly that type which are adapted to securely retain a pencil or pen-holder within the pocket of a garment.

The object of my invention is to provide a cheap, and simple, yet reliable and effective clip, free from elastic bands of rubber, coiled springs and the like which gradually lose their resiliency and become ineffective.

Having thus indicated the nature and objects of my invention and in order to enable those skilled in the art to utilize and more fully comprehend the same, I will now proceed to describe the preferred mode of constructing and utilizing the same, reference being had to the devices disclosed in the accompanying drawings forming a part of this specification.

In the accompanying drawings: Figure 1 is a plan view of a piece of sheet spring-metal stamped out with suitable dies, preparatory to rolling the same. Fig. 2 is an elevation of 30 a pencil fragment showing the completed clip in position thereon. Fig. 3 is a sectional side elevation taken on the central line $c-c$ in Fig. 2, of the clip, showing the pencil in elevation.

Referring to the drawings: the reference numeral 1 designates a curvilinear body, preferably as shown, a spring sheet-metal barrel or "split-ring", which is provided with recesses 2 and 4 and a projecting spring-arm 3. This spring-arm is of a compound-curve configuration and is arched in cross-section across the greater portion of the width thereof at its upper end where the said compound-curve is of shortest radius. The said arch being more pronounced in curvature than the curvilinear body is not concentric therewith and being of greater curvature the radius of curvature of the arch is considerably less than the radius of curvature of the curvilinear body. At the point of junction of the spring-arm with the curvilinear body the arm conforms substantially in transverse curvature to the curvature of said body, as the arch does not extend throughout the length of said spring-arm. The end of said spring-arm is provided

with roughened V-shaped grooves produced by scoring the same and the greater portion of the shank distant from said grooves is arched in cross section, preferably having a convex configuration, as shown at 6. In order to afford a greater degree of friction of the clip and pencil, the barrel is provided with openings 7, which present additional edges to the pencil and serve to prevent the displacement of the same longitudinally thereof. The spring-arm is integral with the curvilinear body and extends both above and below the point of junction therewith and the end 8 is decidedly upturned to permit of certain engagement of the same with the opposite side of the rim of a pocket from that contacting with the pencil. A neck 9 unites the clip into an integral piece and directly receives the strains resulting from thrusts upon the end of the spring-arm upon contacting with the rim of a pocket.

The reference letter *a* designates a fragment of a pencil.

The chief advantages of the structures herein described reside in the non-slipping features both with regard to the pencil and also to the rim of a pocket. Moreover these features are combined with an extraordinary degree of strength and there is an entire absence of elastic bands, which are subject to deterioration.

Various modifications can be made within the scope of the appended claims without departing from the spirit of my invention.

Having thus described my invention I claim:

1. A clip adapted to slidably engage a garment, comprising a curvilinear body adapted to engage a rigid support, a spring-arm of a compound-curve configuration and arched in cross-section across the greater portion of the width thereof at the point where the curve is of shortest radius, the radius of curvature of said arch being considerably less than the radius of curvature of said curvilinear body, and said arm being integral with said body and extending both above and below the point of junction therewith and conforming substantially in transverse curvature, immediately adjacent the point of junction with said body, with the curvature of said body.

2. A clip, comprising a split-ring-shaped, tubular barrel, provided with recesses extending inwardly from the upper and lower edges respectively of said barrel, a trans-

versely extending neck between said recesses, a spring-arm comprising a compound-curve and arched in cross-section at its point of greatest curvature across substantially its entire width, said arm being integral with the neck between the aforesaid top and bottom recesses and extending both above and below the same, and a plurality of V-shaped grooves at the lower end of said spring-arm adapted to increase the friction of the end

upon an opposing surface without preventing sliding engagement of the end with such surface, substantially as described.

Signed at New York, in the county of New York, and State of New York, this 16th day 15 of February, A. D. 1907.

WILLIAM F. OAKLEY.
